UNITED STATES PATENT OFFICE.

GEORGE H. TREADGOLD, OF PORT HURON, MICHIGAN, ASSIGNOR OF ONE-THIRD TO PETER HANES, OF GLOVERSVILLE, NEW YORK.

TYPE-WRITING MACHINE.

SPECIFICATION forming part of Letters Patent No. 631,833, dated August 29, 1899.

Application filed December 15, 1898. Serial No. 699,397. (No model.)

To all whom it may concern:

Be it known that I, GEORGE H. TREADGOLD, a citizen of the United States, residing at Port Huron, in the county of St. Clair and State of Michigan, have invented certain new and useful Improvements in Type-Writing Machines, of which the following is a specification, reference being had therein to the accompanying drawings.

10 My invention relates to that class of type-writing machines in which a rotary type-wheel is employed which is rotated differentially by the keys of the machine to bring the proper type into alinement with the paper roll and is then moved laterally to strike said type against the paper.

The invention consists in the peculiar construction, arrangement, and combination of parts, all as more fully described and claimed.

20 In the drawings, Figure 1 is a vertical longitudinal section through my type-writing machine. Fig. 2 is a cross-section on line $x\ x$, Fig. 1, looking toward the right. Fig. 3 is a sectional elevation of the under side of the 25 type-wheel and its actuating mechanism.

Fig. 4 is a section on line $y\ y$, Fig. 3. Fig. 5 is a horizontal section of the paper-carriage substantially on line $z\ z$, Fig. 1. Fig. 6 is a 30 sectional perspective view of a portion of the feed-bar of said carriage. Fig. 7 is a section on line $w\ w$, Fig. 5. Fig. 8 is a section on line $v\ v$, Fig. 5. Fig. 9 is a section on line $u\ u$, Fig. 8, and Fig. 10 is an elevation showing the segmental rack-bar forming part of the 35 rotating mechanism for the type-wheel.

A is the type-wheel, which is provided on its periphery with a series of circumferential rows of type, the drawings showing three of said rows $a\ a\ a^2$. This wheel is mounted upon 40 a shaft B, which is journaled in a bearing in a rock-frame C. This rock-frame is bifurcated at its lower end and is pivoted to a transverse shaft D, secured to the frame of the machine. Between the bifurcations of the frame

45 Care arranged oppositely-beveled gear-wheels E and E' , adapted to mesh with a beveled pinion F, secured to the shaft B. The gear-wheels E and E' are secured, respectively, to the sleeves or tubular shafts G and G' upon 50 the shaft D. At the outer ends of these sleeves are arranged pinions H and H' .

I are the keys of the machine, which are fulcrumed upon a transverse rod or shaft J in front of the shaft D, being provided with suitable finger-pieces I'.

55

K and K' are universal bars extending, respectively, across the keys on the right and left of the center of the machine. These bars are preferably secured to the rock-arms K^2 , pivoted upon the shaft J.

60

Each of the keys I is provided with a finger or shoulder b , extending beneath one of the universal bars K and K' . These fingers b are arranged to be at different distances from the bars K and K' , so that in the actuation of the 65 keys there will be a different degree of lost motion in each from all the others.

L and L' are segmental racks adapted to mesh with the pinions H and H' , respectively, and preferably pivotally secured upon the 70 shaft J and resting normally upon the universal bars K and K' , respectively.

M is a universal bar extending completely across the keys of the machine and in the path of fingers c, preferably projecting from the 75 under sides of the keys. These fingers, like the fingers b , are differentially arranged, so as to give a greater or less degree of lost motion of the keys before the fingers strike against the bar M.

80

The rock-frame C is provided with a segmental arm N, extending around concentric with the shaft B and provided at one point with a notch N'.

O is a rod connected to the rock-arm M', to 85 which the bar M is secured and extending upward therefrom. This rod is preferably provided with a longitudinal slot O', through which the shaft D passes, and at the upper end of the rod is arranged a lug or detent 90 O^2 , adapted to engage with the notch N' in the segmental arm N.

P is a wedge-block secured to a spring-arm P', extending from the end of the arm N and adapted to be pressed by said spring into engagement with the opposite gear-wheels E and E' , so as to lock the same from rotation. This wedge-block is, however, normally held out of engagement with said gears by a lug O^3 on the rod O when the latter is in a position to 100 hold the detent O^2 in engagement with the notch N'.

The type-wheel A is so secured to the shaft B as to be free to slide longitudinally thereon.

Q is a sleeve longitudinally slidably secured upon the bearing of the frame C, in which the shaft B is journaled and held from rotation thereon by a feather or in any other suitable way. This sleeve has a hooked engagement with the wheel A, preferably by forming thereon the annular grooved flange 10 d, engaging with the annular flange e upon the wheel A.

R is a cam pivotally secured at R' to the frame C and engaging with the lug or anti-friction-roll R² upon the sleeve Q, preferably 15 by being provided with the inclined slot R³, into which said roll projects. On the opposite side of the pivot this cam is provided with an actuating-arm R⁴, which extends into proximity to the shaft D.

S is a sleeve longitudinally sliding upon the sleeve G' on the shaft D and provided with lugs or rolls S' on opposite sides of the arm R⁴.

T is a cam engaging with an annular groove 25 S² upon the sleeve S and adapted to move the same longitudinally upon the shaft without interfering with its rotary movement thereon. This cam T is adapted to be actuated by the case-keys T' and T², one of which moves it in 30 one direction and the other in the opposite direction.

U is an inking-roll connected to the free end of an arm or frame U', which is adapted to hold it in the path of the type-wheel A.

35 The paper-carriage of my machine comprises the usual paper-roll V, which is mounted upon a reciprocating frame V'. This frame is provided with a bar V², which engages with a groove V³ in the base W of the machine and is preferably supported upon antifriction-rolls V⁴. The upper side of the bar V² is provided with a series of transverse grooves f f', the former being at right angles to the bar and the other inclined so as to form 40 a continuous zigzag slot from one end of the bar to the other. The bottoms of the slots f are inclined upward from front to rear, so as to form steps or drops g at the point where they merge in the slots f'.

50 X is a bar extending at right angles to the bar V² and slidably secured in bearings upon the base of the machine. This bar is provided at its rear end with a downward-projecting lug or antifriction-roll h, adapted to 55 engage with the grooves f f' in the bar V². At its outer end the bar X engages with the arm Y, connected to a universal bar Y', extending under all of the keys of the machine, this arm being so arranged that when any 60 one of the keys is depressed it will impart a forward movement to the bar X, which will cause the roll h to travel from the front end of the groove f to the rear thereof.

X' is a spring for returning the bar X to its 65 initial position.

The parts being constructed as thus far shown and described, the operation of the ma-

chine is as follows: Whenever one of the keys I is depressed—as, for example, one of the keys on the left-hand side of the machine—it 70 will cause the finger b to strike against the universal bar K, causing the latter to lift the segmental rack L and impart a rotary motion to the pinion H on the sleeve G. This will cause the bevel-gear E to rotate the pinion F 75 on the shaft B and turn the type-wheel A a certain distance, the amount of rotation depending upon the degree of lost motion before the finger b strikes the arm K. At the same time the movement of the key I will cause the 80 finger c to travel into contact with the universal bar M and cause the latter to rock the arm M' and lift the bar O, which will first disengage the lug O² from the notch N' and then by the withdrawal of the lug O³ permit the 85 wedge P to lock the gear-wheels E and E'. This locking of the gear-wheels will of course prevent further rotation of the type-wheel A; but inasmuch as both gears E and E' are free to rotate upon the shaft D the further movement of the key I will cause a rocking of the 90 frame C, carrying the type-wheel A downward and causing the proper type to strike against the paper on the roll V. Upon releasing the pressure on the key I the reverse 95 movement will be imparted to the various parts, the frame C and type-wheel being first lifted by a spring C' until the detent O² again engages with the notch N' and the lug O³ then 100 disengaging the wedge P from the gear-wheels E and E', allowing the former to be rotated until the type-wheel A is again brought into its normal position. The rock-arm M' and bar O are returned to their normal positions either by gravity or by a spring. (Not shown.) 105 Thus, in brief, the operation of each key will first impart a rotary movement to the type-wheel, then unlock the frame carrying said wheel and lock the wheel from further rotation, and finally will cause the throwing down 110 of said wheel into contact with the paper.

Inasmuch as it is customary in the construction of type-writing machines to have each key represent a number of different characters, it is necessary to provide means for moving the wheel A longitudinally upon the shaft B to bring in one of the rolls a, a', and a² into proper position to strike against the roll V. This mechanism which I have already described is operated as follows: The cam T is 115 actuated by suitable keys, preferably two in number, T and T², representing, respectively, the type in the row a' and the type in the row a², while the central row a is normally in line with the paper-roll. The movement of the cam 120 T will impart a longitudinal movement to the sleeve S, which will cause the lug or rolls S' to rock arm R⁴ of the cam R, causing the latter to move the sleeve Q longitudinally on the frame C and impart a corresponding longitudinal movement to the type-wheel A. This will bring one or the other of the rows 125 a' a² into proper alignment with the paper-roll. Each actuation of the key I will also im- 130

part motion to the universal bar Y' and the arm Y, carried thereby, which will cause the rearward movement of the bar carrying the roll h to the rear end of the slot f, with which it engages, and allow it to drop down the step g into the slot f'. As the key I is released the spring X' will again retract the rod X; but inasmuch as the roll h has dropped down the step or shoulder g it is compelled in its return movement to travel the slot f', and this will cause the bar V² to be moved longitudinally. Each successive actuation of a key will thus cause the bar V² to move from one of the grooves f to the next adjacent one, which will carry the paper-roll the proper distance for another letter.

When the carriage has traveled completely across the machine or whatever distance is desired by the operator, it may be returned by the mechanism illustrated in Figs. 5, 8, and 9 of the drawings, in which i is a lever pivoted upon the bearing j, in which the bars X and V² are slidably secured. k is a pin connected to the end of the lever i and extending down in a slot in the bearing j in the path of a shoulder l on the bar X, being so arranged that it will normally hold said bar from being retracted by the spring X' far enough to disengage the roll h from the slot f of the bar V². When, however, the pin k is lifted by the actuation of the lever i, the bar X is free to be drawn so as to disengage the roll h from the slot f, and the carriage may then be moved backward to the proper position.

35 The inking-roll U is so arranged in relation to the wheel A that each time the wheel is thrown down the roll will be drawn across the face of the type to ink the letter and will be pressed out of the way before the wheel 40 comes in contact with the paper. This mechanism, however, forms no part of my present invention.

What I claim as my invention is—

1. In a type-writing machine, the combination with a type-wheel and key-actuated means for rotating said wheel and for moving it laterally against the printing-surface, of means for normally locking said roll from said lateral movement, and means for simultaneously arresting the rotation of said wheel and for unlocking said locking means.

2. In a type-writing machine, the combination with the rotating type-wheel of an actuating-shaft therefor on which said wheel is longitudinally slidably secured, a rock-frame

in which said shaft is journaled, a non-rotative sleeve slidably secured upon said rock-frame and having a swivel connection with said wheel, a cam for reciprocating said sleeve having an actuating-arm extending in toward the axis of said rock-frame and means for moving said arm to shift said wheel in different positions on said shaft.

3. In a type-writing machine, a feed for the paper-carriage comprising a bar on the carriage-frame having a zigzag slot formed therein, a bar extending transversely of said frame-bar in the plane of one section of said zigzag slot, and having a lug or roll engaging with said slot, means for moving said latter bar by the depression of any one of the keys of the machine to cause said lug or roll to travel across said parallel slot-section into the angling section thereof and means for retracting said bar on the release of said key and thereby causing said roll to travel the inclined section of said slot and feed said frame-bar forward.

4. In a type-writing machine, a feed for the carriage comprising the bar V² on the carriage-frame having a zigzag slot formed therein consisting of the perpendicular cross-slot sections f and angling slot-sections f' with the step or drop g at the point of junction, the bar X extending parallel to the planes of the slots f and having the lug or roll h engaging said slot, means for actuating said latter bar by the depression of any one of the keys to cause said lug or roll to travel across said slot-section f and drop into the section f', and a spring for returning said bar for the purpose described.

5. The combination of the bar V³ having perpendicular and inclined cross-slots f and f' forming a continuous zigzag channel along the bar of a key-actuated bar adapted to be reciprocated across said bar V³ and having a lug or roll engaging with said zigzag channel, a pin for limiting the movement of said reciprocating bar to prevent the disengagement of said lug or roll from said slot and a lever for retracting said pin to permit of the disengagement of said roll and the free movement of said bar V³.

In testimony whereof I affix my signature in presence of two witnesses.

GEORGE H. TREADGOLD.
